UNITED STATES PATENT OFFICE.

GUSTAVE SONIAT DU FOSSAT, OF NEW ORLEANS, LOUISIANA.

CURB.

SPECIFICATION forming part of Letters Patent No. 775,623, dated November 22, 1904.

Application filed November 13, 1903, Serial No. 181,037. (No model.)

To all whom it may concern:

Be it known that I, GUSTAVE SONIAT DU FOS-
SAT, a citizen of the United States, residing at
New Orleans, in the parish of Orleans and
5 State of Louisiana, have invented new and use-
ful Improvements in Curbs, of which the fol-
lowing is a specification.

This invention relates to the construction of
curbing, and has for its principal object to pro-
10 tect curbs formed of concrete or similar other
material from breakage and wear.

A further object of the invention is to pro-
vide a curb-protector or corner-shield that is
anchored to the curb during the process of
15 construction.

With these and other objects in view, as will
more fully hereinafter appear, the invention
20 consists in the novel construction and arrange-
ment of parts hereinafter fully described, illus-
trated in the accompanying drawings, and partic-
ularly pointed out in the appended claims,
it being understood that various changes in
25 the form, proportions, size, and minor details
of the structure may be made without depart-
ing from the spirit or sacrificing any of the
advantages of the invention.

In the accompanying drawings, Figure 1 is a
transverse sectional view of a curb constructed
30 in accordance with my invention. Fig. 2 is a
detail perspective view of a portion of the
protecting-strip detached. Fig. 3 is a similar
view of the anchor employed for holding the
protecting-strip in position.

Similar numerals of reference indicate cor-
35 responding parts throughout the several fig-
ures.

The curb is formed of concrete or analogous
material, and during the process of construc-
40 tion anchoring-bars or supports 1 are em-
bedded in the material, these serving to receive
a protecting-strip 2, which extends along the
full length of the curbing and is preferably
formed in sections of convenient length. Each
45 anchor comprises a downwardly-extending
head or tongue 3, provided with a lateral ex-
tension which forms the main body of the
anchor and which is preferably disposed in a
horizontal plane during the process of manu-
50 facture, said extension being formed with an
enlarged head having a mortise 4 formed

therein, that is preferably undercut or dove-
tailed in shape, as clearly shown in Fig. 3 of
the drawings. These anchors are disposed at
suitable intervals throughout the length of
the curbing and serve to receive the protect-
55 ing-strip or corner-bar 2. The head of the
protecting-strip is preferably round, as indi-
cated at 4', to conform to the contour of the
curb, and the converging side walls 5 of the
head are connected by a web 5' with a tenon
60 of a shape corresponding to that of the mor-
tise 4.

In the manufacture of the curb the lengths
of protecting-strips are first provided with the
anchoring devices, these being spaced at suit-
able intervals, and then the whole is supported
during the manufacture of the curb. Curbs
65 of this class are usually provided with a ce-
ment casing, and after the body of the curb
has been formed the anchoring devices and
protecting-strip may be placed in position
70 within the yieldable mass of concrete, after
which the cement finish or additional concrete
may be applied.

It is obvious that the shape of the protect-
75 ing-strips may be altered in any manner and
that the construction and arrangement of the
anchoring devices or supports may be changed
without departing from the invention.

Having thus described the invention, what 80
is claimed is—

1. In a curb-protector, an anchor having a
mortise upon one side thereof disposed diag-
nally to and in the plane of the body of the
85 anchor, and a corner-bar provided with a
tenon to fit the mortise, whereby said bar is
disposed at an acute angle to the anchor.

2. A corner-bar provided with a tenon hav-
ing converging side walls, and an anchor com-
prising a body portion having enlarged heads
90 at its opposite ends, one of said heads being
provided with a mortise adapted to receive
said tenon.

3. A corner-bar having a dovetailed tenon,
and an anchor comprising a head or tongue
having a lateral extension therefrom provided
with a mortise adapted to receive said tenon.
95

4. In a curb-protector, a horizontally-dis-
posed anchor having a laterally-disposed mor-
tise upon the upper face thereof disposed in the
100

plane of the body of the anchor, and a corner-bar provided with a tenon to fit such mortise and supported diagonally above such anchor at the intersection of the front and top surfaces 5 of the curb.

5. A metallic curb-protector comprising a bar and an anchor; one of the said elements having a web and an enlargement thereon, both extending in the direction of the length 10 of the bar, and the other having a notch or seat disposed in the direction of the length of the bar and comprising an outer reduced portion receiving the web of the first-mentioned element, and an inner comparatively large 15 portion receiving the enlargement on the web, whereby when one of the elements is slipped laterally into engagement with the other, the said elements are connected of themselves.

6. In a curb, the combination with concrete 20 or other material of which the major portion of the curb is formed; of a metallic protector embedded in the concrete or other material, and comprising the following elements, viz: a bar having a head positioned at the corner 25 of the concrete or other material, and an anchor; one of the said elements having a web and an enlargement thereon, both extending in the direction of the length of the bar, and

the other having a notch or seat disposed in the direction of the length of the bar and comprising an outer reduced portion receiving the web of the first-mentioned element, and an inner comparatively large portion receiving the enlargement on the web. 30

7. In a curb, the combination with concrete 35 or other material of which the major portion of the curb is formed; of a metallic protector embedded in the concrete or other material, and comprising a bar having a head positioned at the corner of the concrete or other material, and also having a web extending inwardly from the head, and an enlargement on the inner portion of the web, and an anchor having a notch or seat disposed in the direction of the length of the bar, and comprising an outer 40 reduced portion receiving the web of the bar, and an inner comparatively large portion receiving the enlargement on the web, and also having a depending arm. 45

In testimony whereof I have hereunto set 50 my hand in presence of two subscribing witnesses.

GUSTAVE SONIAT DU FOSSAT.
